INVENTOR.

Geo. P. Kimmel ^{b1}
ATTORNEY.

UNITED STATES PATENT OFFICE.

CLYDE J. McNERNY, OF FORT MADISON, IOWA.

ATTACHMENT FOR INTERNAL-COMBUSTION ENGINES.

Application filed July 30, 1921. Serial No. 488,627.

To all whom it may concern:

Be it known that I, CLYDE J. McNERNY, a citizen of the United States, residing at Fort Madison, in the county of Lee and State of Iowa, have invented certain new and useful Improvements in Attachments for Internal-Combustion Engines, of which the following is a specification.

This invention relates to pre-heating attachments for internal combustion engines.

The object of the invention is to provide means for generating steam from the heat of the exhaust manifold and injecting it into the intake manifold of an internal combustion engine, whereby the atomized fuel may be preheated and commingled with the steam before entering the engine cylinders, thereby increasing the explosiveness of the mixture.

Another object of the invention is to provide an attachment of this character which is simple and compact in construction, and which may be readily attached to the engine of any design of motor vehicle without altering any part thereof, or interfering with the functioning of the engine so provided, or with any of its accessories.

With these and other objects in view, the invention consists in certain novel features of construction as hereinafter shown, described and claimed.

In the accompanying drawings:

Figure 1 represents a side elevation of an engine equipped with this improved attachment.

Fig. 2 is a longitudinal vertical section of the attachment; and

Fig. 3 is an end elevation of the attachment taken from the front portion thereof.

Having more particular reference to the drawings in connection with which like reference characters will designate corresponding parts, the attachment constituting this invention comprises a casing 1 of suitable metallic material, preferably aluminum and further, although not necessarily, made rectangular in configuration. This casing 1, has its bottom 2, shaped to snugly fit over the exhaust manifold E, of an internal combustion engine, said bottom being shown concavo-convex for this purpose.

This casing 1, has a threaded inlet opening 3, at one end near the bottom thereof, as is shown clearly in Figs. 1 and 2, designed to receive an elbow shaped coupling 4, which is threaded at its free end for the reception

of a union 5, which connects the coupling 4 with a pipe 6, leading from the water jacket of the engine, it being understood that said pipe 6, or conduit is tapped into the water jacket in a suitable manner. A needle valve 7, is located in the conduit 6, for controlling the water fed from the engine jacket to said conduit.

Another screw-threaded opening 8, is formed in the upper portion of the casing 1, near its front end and serves to permit the establishment of communication between the engine intake manifold I and said casing 1, a conduit 9 being engaged in said opening at one end and in the intake manifold I of the engine at its other end, as is shown, clearly in Fig. 1. As shown, a screw threaded nipple 10, connects the pipe 9, with the casing and said pipe is provided preferably adjacent the manifold I, with a needle valve 11, for controlling the steam supplied from the casing 1 to said manifold.

The conduit or pipe 6, is provided intermediate its ends in the top portion thereof with an aperture 6^a, for the admission of air to the conduit and to prevent siphoning of the water from the water jacket through said pipe.

The elbow-shaped coupling 4, at a point opposite the inner end of the union 5, is formed with a transversely extending aperture or port 4^a, for the entrance of air to the casing 1, in a manner presently to be described.

A pair of obliquely disposed apertures 12, are formed in the front wall of the casing 1, at the lower portion thereof, preferably adjacent the connection of said casing with the bottom 2, to provide for the escape of the water of condensation when the engine is not in operation, so that there will be no danger of water instead of steam being sucked into the intake manifold I when the engine is started.

In the operation of this improved attachment, the parts being in the position shown in Fig. 1, the needle valve 7, is adjusted so that a very small quantity of water will be fed to the casing 1, being preferably supplied in drops so that when it strikes the heated bottom 2 of the casing, steam will be immediately generated. The water dropping from the inner end of the union 5, will cause air to be sucked into the coupling 4, through the opening 4^a, and passed with the water into said casing. The needle

valve 11, having been properly adjusted the steam generated in the casing 1, will be drawn by suction through the conduit 9, into the intake manifold I where it will commingle 5 with the fuel supplied from the carbureter and pass with said fuel into the engine cylinders. This combining of the steam with the air and gas drawn in from the carbureter produces a highly explosive mixture.

10 If any dirt or sediment should lodge on the seat of the needle valve 7, it would cause a leakage of water into the casing 1, from whence it would flow, when the engine is idle, into the manifold I and back into the carbureter. This would render starting of the engine difficult, if not impossible, and to overcome this the apertures 12, are provided so that any water which may collect in the casing 1, will drain off through these 15 inclined apertures 12, and flow out onto the ground.

From the above description, it will be obvious that this attachment may be applied to an engine by simply tapping the conduit 6, into the water jacket thereof at one end, and by tapping the conduit 9 into the manifold I, as shown in Fig. 1, the engine being otherwise unaltered.

Obviously the increase of the speed of the 30 engine will increase the supply of air and steam to the intake manifold and in consequence proper functioning of the invention will be insured.

The preferred embodiment of the invention 35 is disclosed in the drawings and set forth in the specification, but it will be understood that any modifications within the scope of the claimed invention may be made in the construction without departing from 40 the principle of the invention or sacrificing any of its advantages.

What I claim is:

1. A steam generator attachment for internal combustion engines comprising a substantially rectangular casing having a bottom arcuate in cross section to snugly fit a portion of the exhaust manifold of an engine, an obliquely disposed drain aperture opening through one side wall of said casing

50 near the lower end thereof, an L-shaped coupling detachably mounted at one end of said casing in proximity to its bottom and provided with an air inlet opening at the upper portion thereof, a union mounted in the upper 55 end of and extending into the coupling and terminating above said opening, a water supply pipe connected to said union, the top of said casing having a steam discharge outlet near the other end thereof, and a nipple mounted in said opening and adapted to be connected with a conduit for conveying steam to the point where it is to be used.

2. A steam generator attachment for internal combustion engines comprising a steam generator, a vertically disposed angle shaped element opening at its lower end into one end of said generator in proximity to the bottom thereof and provided near its top with an air intake, a water supply connection leading from the water space of an engine and opening into said element at a point above said air intake and provided intermediate its ends with an air vent, a valve mounted in said connection, a steam supply pipe leading from one end of the top of said generator, and a valve mounted in said supply pipe.

3. A steam generator attachment for internal combustion engines comprising a steam generator mounted on and overlapping the exhaust manifold of an engine of a motor vehicle, an angle shaped element opening at its lower end into one end of said generator in proximity to the bottom thereof and provided near its top with an air intake, a water supply connection leading from the water space of the engine and opening into said element at a point above said air intake and provided intermediate its ends with an air vent, a valve mounted in said connection at the inlet end thereof, a steam supply pipe leading from one end of the top of said generator, and a valve mounted in the outlet end of said supply pipe.

In testimony whereof, I affix my signature hereto.

CLYDE J. McNERNY.
